ROCKING TOY

Laurie Jay Campbell, Erie, Pa., assignor to Louis Marx
& Co., Inc., New York, N.Y., a corporation of New York

Filed Feb. 4, 1970, Ser. No. 21,261

Term of patent 14 years

Int. Cl. D21—02

U.S. Cl. D34—15

FIG. 1

FIG. 2

FIG. 3

FIG. 1 is a front right side perspective view of a rocking toy embodying my new design;

FIG. 2 is a left side elevational view thereof; and
FIG. 3 is a rear elevational view thereof.

I claim:

The ornamental design for a rocking toy, as shown.
